UNITED STATES PATENT OFFICE

JOSEPH AMELOTTE, OF LYNN, MASSACHUSETTS

SANITARY TOOTHBRUSH HOLDER

Application filed March 22, 1929. Serial No. 349,249.

This invention relates to a tooth brush holder and has for its object to provide a novel tooth brush holder which is perfectly sanitary, which is constructed so that the tooth brush is entirely enclosed when it is not in use and which is further so constructed that the tooth brush may be readily removed from it or replaced in it.

In order to give an understanding of the invention I have illustrated in the drawing a selected embodiment thereof which will now be described after which the novel features will be pointed out in the appended claims.

Fig. 1 is a perspective view of a tooth brush holder embodying my invention showing it in closed position;

Fig. 2 is a similar view showing the manner in which the holder is manipulated to give access to the tooth brush;

Fig. 3 is a section on the line 3—3, Fig. 1 showing the holder closed;

Fig. 4 is a similar view showing the holder open;

Fig. 5 is a section on the line 5—5, Fig. 1; Fig. 6 is a section on the line 6—6, Fig. 1.

My improved tooth brush holder comprises a supporting member 1 which is in the form of a plate adapted to be secured to a wall or fixture of any character by means of screws 2, and a brush holding member 3 that is pivotally mounted on the supporting member 2 and forms a pocket to receive the tooth brush 4.

The supporting member 1 is preferably made of sheet metal and is formed at each end with a yieldable ear or flange 5, said ears or flanges forming the ends of the pocket or chamber 6 in which the tooth brush 4 is received. The holding member 3 may be made of various materials but is preferably constructed of sheet metal and is pivotally mounted in the supporting member swinging in one direction into closed position and in the other direction to open and deliver the brush. The holding member is curved in cross section as shown in Fig. 3 having a curved lower portion 7 which forms a pocket to receive the brush. This lower portion also serves as the bottom of the chamber 6 while the rearwardly inclined upper portion 8

forms the front side and top of the chamber 6. The member 3 is provided with trunnions 9 which are received in bearings located in the extensions 10 formed on the flanges 5. The member 3 is provided with bosses 11 situated approximately at the junction of the curved portion 7 and the upper portion 8 of the member 3. These bosses form a firm support in which the trunnions 9 are fixed. The pivotal axis of the member 3 is located somewhat above the bottom thereof and as this axis is at the outer edge of the member it is apparent that when the tooth brush is in the holder the weight of the tooth brush on the bottom 7 will tend to keep the member 3 in closed relation with the upper edge 12 thereof resting against the top edge of the supporting member 1.

The lower edge of the holding member 3 is so shaped as to permit said member to turn about its pivotal axis from the position shown in Fig. 3 to that shown in Fig. 4. When the holder is in its closed position the chamber 6 encloses the brush thus protecting it from insanitary influences. When the person desires to remove the tooth brush from the holder he presses against the curved lower portion thereof with his fingers as shown in Fig. 2 thus swinging the holding member 3 into the position shown in Figs. 2 and 4. As the holding member 3 swings into this position the weight of the tooth brush is transferred from the bottom 7 to the side portion 8 as shown in Fig. 4 and thus the weight of the tooth brush tends to swing the holding member 3 into a reverse position. As the member 3 swings into the position shown in Fig. 2 the tooth brush will move off from the portion 8 into the hand of the user as shown in dotted lines Fig. 2. It is not necessary therefore for the user to pick the tooth brush out of the holder as the simple act of swinging the holding member 3 into its reversed or inverted position will allow the brush to move into the hand. When the tooth brush is replaced in the holder and the latter is swung into its upright position shown in Fig. 3 the weight of the tooth brush holds the holding member 3 closed as it is

applied to the portion 7 thereof below the pivotal axis.

Owing to the novel features of the device it becomes a very simple matter to maintain the device in a strictly sanitary condition. When the device is in open position the holding member 3 swings clear of the supporting member 1 thus enabling the holding member 3 to be very readily cleansed by a simple lengthwise motion of a cloth or other cleansing means. If it be desired to thoroughly sterilize the holding member it may be removed. The flanges 5 are resilient and by longitudinal movement of the holding member the trunnions 9 are freed from their bearings in extensions 10 of the flanges 5. Furthermore provision is made for the proper ventilation of the holder. A narrow portion of the holding member 3 is cut away at its upper edge at 13 which forms an air-duct when the device is in closed position. When in this position the inner edge of the curved portion 7 of the holding member is spaced away from the supporting member 1 which provides an additional duct for the passage of air. Thus the device is constantly vented and at the same time affords proper protection for the brush.

Having thus described the invention, what is claimed as new, and desired to be secured by Letters Patent, is:

1. A brush holder comprising a flat vertically disposed supporting plate having at its ends flanges provided with bearings located at a distance from said plate, a swinging holder for the brush pivotally mounted in said bearings having a base portion forming a pocket for said brush and a closure portion extending therefrom rearwardly into engagement with the upper portion of said plate above and protecting the brush and means pivotally connecting said holder to said bearings operable to cause said holder to be retained by gravity selectively in closed position or in open position, said holder being operable when the brush is enclosed therein by upward pressure of the fingers on the base portion thereof to invert the holder and deliver the brush into the hand, said end flanges being resilient whereby said holder may be moved longitudinally to remove the same from the support to permit thorough cleansing of the device.

2. A tooth brush holder comprising a flat vertically disposed supporting member adapted to be secured to a wall or fixture and having resilient flanges at its ends said flanges provided with bearings, a brush holding member having trunnions at its ends to be detachably received by said bearings, said brush holding member having a concave lower portion to receive a tooth brush and a rearwardly inclined upper portion extending into engagement with the upper portion of said supporting member above and protecting

the brush having an opening therein, the pivotal axis of the brush holding member being situated outwardly from its center of gravity and above the concave portion, whereby the weight of the tooth brush will retain the holder closed with its upper edge resting against the top of the supporting member and the inner edge of the concave portion spaced therefrom and whereby when the brush is enclosed therein upward pressure of the fingers upon the base portion thereof will cause the holder to be inverted and deliver the brush into the hand.

In testimony whereof, I have signed my name to this specification.

JOSEPH AMELOTTE.
